CAN FILLING MACHINE

Charles H. Ayars, Salem, N. J., assignor to Ayars
Machine Company, Salem, N. J., a corporation
of New Jersey

Application November 10, 1936, Serial No. 110,053

20 Claims. (Cl. 226—100)

This invention relates to a can filling machine, and has particular reference to can filling machinery which is capable of operating at high speed, and which deposits discrete solid material and liquid in each can as it passes under the influence of measuring and depositing mechanism.

The machine of this invention is an improvement on applicant's Patent No. 1,533,536, granted April 14, 1925.

In can filling machinery, such as that disclosed in the above patent, and where both granular or discrete solid material is to be deposited in each can along with liquid, such as brine, it has been found that in order that the brine may find its way into all the voids between the spherical or ovate discrete solids, and finally assume a height above the solids, that the speed of the machine must be curtailed, or the machine must be made larger so as to have more measuring pockets and directing funnels, so that the can will remain under the same for a greater length of time.

It has also been found that in machines of the character shown in the above mentioned patent, and where the adjustment for the telescopic cups is on the upper turret, which is removed for cleaning the machine, that the adjustment is oftentimes lost, during the washing process, so that upon the replacement of the upper turret, it is necessary to again adjust the machine for the grade of solids to be canned. It also follows that adjustments must be made for every different grade of solids being filled in the cans and when this adjustment has once been obtained and lost, by adjustment for a different grade, no means is provided for again setting the machine for the former grade, except the mere "cut and try" expedient.

One of the objects of the present invention is to provide in a high speed canning machine, means for uniformly filling the cans with discrete solids and liquid surrounding and covering said solids.

Another object of the invention is to provide a machine wherein the liquids and solids may each be measured to any predetermined quantities, and each regulation cannot be disturbed by removing turret parts for cleansing the machine.

A still further object of the invention is to provide a can filling machine in which means are provided for indicating the capacities of the measuring cups, so that when once adjusted for grade, the machine may be quickly readjusted for other grades without experimenting.

A still further object of the invention is to provide in a can filling machine, a liquid supply which is operative only during the operation of the can filling machine.

According to the invention, the can filling machine has means for feeding cans into operative position for filling, means for supplying a measured quantity of liquid to each can during its travel through said feeding means, a pair of measuring devices each comprising an upper and lower turret providing telescopic measuring cups, one of said devices having means for supplying discrete solid material to its cups, and the other having means for supplying liquid to its cups, a distributing member having funnels each adapted to successively receive the contents of a solid material cup and a liquid cup, and to direct same into a can to be filled; each of said lower turrets being rotated by a hollow shaft; each upper turret having a shaft secured thereto and extending through said hollow shaft; said shafts each provided with means for raising and lowering means, whereby the relationship between the turrets is adjusted to alter the capacities of the cups, and separate means each operated by one of said last-named means for indicating the cup capacity. The last-named means is a dial having a pointer operated through the means which operates the non-rotating shaft. The liquid supply is provided with a valve therein operated by means of a governor which in turn is operated by the mechanism which operates the turrets in order to open the said supply, and which said governor closes said supply when the machine is at rest.

The drawings illustrate embodiments of the invention, and the views therein are as follows:

Figure 1 is a vertical sectional view of the machine showing parts thereof broken away.

Fig. 1A is a small cross-sectional view showing the manner in which the solid material hopper is rotated, and is taken on the line 1A—1A of Figure 1.

Figure 2 is a top plan view of the same with certain of the parts removed.

Figure 3 is an enlarged top plane view of the liquid or brine pot, which supplies a measured quantity of liquid to each can during the movement of the can into the machine proper.

Figure 4 is a vertical sectional view taken on the line 4—4 of Figure 3.

Figure 5 is a side elevation of the machine with a part of the hopper and the standards broken away, and shows the manner of adjusting the cups of the solid material measuring device, and the means for indicating the capacity of the cups.

- Figure 6 is an end view of the same.
- Figure 6A is a side view of a button employed in the indicating device for marking a desired cup capacity.
- 5 Figure 7 is a side elevation of the machine used for adjusting the capacity of the liquid measuring cups, and the means for indicating the capacity to which the cups have been adjusted.
- Figure 8 is a front elevation of the same.
- 10 Figure 9 is a view showing one end of the machine with certain of the parts broken away, and with the governor operated valve shown in section.
- Figure 10 is a small detail section taken on the line 10—10 of Figure 9.
- 15 Figure 11 is a vertical sectional view of the machine similar to Figure 1 except that the turn operating shafts are split.
- The can filling machine shown in Figures 1 and 2 is designed for belt driving, the belt extending over the pulley 16 on the main shaft 17. While a pulley has been shown it will, of course, be understood that the machine may be direct motor driven or may be motor driven through a 20 chain of gears, so as to impart the desired speed to the can filling devices. The main shaft 17 has a bearing 18 mounted on a bed plate 19, and its outer end is provided with a hand wheel 21 for operating the machine manually, when desired. The main shaft 17 has clutch mechanism 22, and a shipper handle 23 for operating the said clutch so that motion is imparted to the operative parts through the operation of the shipper handle engaging the clutch located in the intermediate position in the main shaft 17. This main shaft 17 has a bevel gear 24 on its inner end which meshes with a bevel ring gear 26 mounted on the hollow shaft 27. In the design shown, the machine is provided with a table 28 which has standards 29 extending to the floor, although the machine may have a cylindrical drum type base with the table at the upper end of the same.
- 30 Cans are dropped into the depository 31 formed by the angle plates 32 and 33, and the lowermost one is taken by the feed screw 34 operated from the main shaft 17, and fed in an upright position to the star wheel 36 mounted on the hollow shaft 27. This star wheel 36 has a downwardly depending sleeve 37 terminating in a gear 38, which said gear meshes with a gear 39 operatively mounted on the star wheel 41, which in combination with the rail 42 discharges the cans from the star wheel 36 after the same have been 35 filled with discrete solid and liquid materials. The can feeding mechanism shown herein is described in detail in applicant's Patent No. 1,475,675, granted November 27, 1923. Located above the tops of the cans A, which rest with their bottoms on the table 28, is an external ring gear 43 provided with collared apertures 44, which apertures are aligned with bottoms of the funnels 46 while the said ring gear is secured on the depending sleeve 41 of the funnel casting 45 by means of a set screw 48. The sleeve 47 is in turn secured to the hollow shaft 27 by the set screw 49. This gear 43 meshes with a pinion 184 on the shaft 186, while an idle gear 183 meshes with the gear 184 and with the gear 182 (see Figure 4) on the auxiliary briner shaft 177.
- 40 This funnel casting 45 has a flanged rim 51 operating on the ledge 52 of supporting frame 53, and this supporting frame has a partition or plate 54 extending entirely over the same, and 45 closing the upper ends of the funnels 46. This plate 54 is shown in Figure 2, and it is provided with a discharge opening 56 which is located with respect to timing in exactly the same position as the discharge opening 62 in my United States Patent No. 1,533,536, first above referred to. The supporting frame 53 and plate 54 are stationary, while the funnel casting 45 and ring gear member 43, by reason of their connection with the hollow shaft 27, are rotatable. Mounted on the upper end of the hollow shaft 27 is a collar 57, and this collar has keys 58 providing rotation for a lower turret member 59, which has its bottom end resting on the plate 54. This lower turret has upstanding circular collars 61 adapted to receive depending collars 62 on the upper turret member 63. The upper turret has a recess 64 in the hub 66 of same into which the end 67 of the shaft 68 is secured by means of a key 69. The hub 66 has a reduced upper end 71 on which is mounted a pinion 72. This pinion 20 meshes with a pinion 73 which, in turn, meshes with the internal gear 74 on the hopper mounting 76, so as to impart rotation to the hopper 77. The hopper 77 extends at one side of the shaft 68, and the telescopic cups formed by the flanges 25 61 and 62 are closed by a cover 78.
- 25 The shaft 68 extends through the hollow shaft 27 and emerges from the bottom thereof, while said hollow shaft has a bearing 82 and a thrust collar 83 on the end thereof, and secured thereto by means of the set screw 84. From this description, it will be seen that the shaft 68 is rotatable with the turrets 59 and 63. The funnel casting 45 is substantially the same as the funnel casting 46 shown in Figures 3, 5 and 13 to 16 of applicant's 30 Patent No. 1,533,536, granted April 14, 1925, and its utility in combination with the telescopic cups of the turret members 59 and 63, and the pockets 86 of the turret members 87 and 88, is explained in detail in that patent, particularly as to the timing of the deposits of discrete solid material from the cups of the former members and liquid from the cups of the latter members into the pockets of the casting 45. The principle there explained and described in detail is exactly the same as the principle of the mechanism of this machine insofar as these parts are concerned, and it will suffice to say that discrete solid material is deposited into the funnels 46 from the cups of the members 59 and 63 prior to the deposit of liquid material into the 35 pockets 89 from the cups of the members 87 and 88. The supporting frame 53 has an oblique platform 91 providing a support for a turret plate 92 located in the bottom of a liquid tank 93. The table 28 has an oblique bearing 94 to accommodate 40 a hollow shaft 95 which extends up through the platform 91 and the bottom of the turret plate 92. This turret member 87 has flanges forming cups 96, the capacity of which cups is regulated by the plugs 97 on the turret member 88. This member 45 is in the form of a plate and its hub 98 is secured to shaft 99 by means of a set screw 101. The upper end of the hollow shaft 95 has a driving disk 102 secured thereto by means of a key 103. This disk has depending arms 104 which engage lugs 106 of the lower turret member 87, while the upper 50 turret member has depending pins 107 which are adapted to pass through holes 108 in the driving disk 102, so that upon the rotation of the hollow shaft 95, the lower turret member and upper 55 turret member will rotate in unison, while the upper turret member is retained in position by its own weight, and may be freely removed from its engagement with the lower turret member, and with the driving disk 102, so that the cups 96 and 75

plugs 97 may be readily cleaned when the machine is shut down, or when the machine is being changed over from one material to another. The hollow shaft 95 has a bevel gear 109 fastened to its lower end by means of a set screw 110, and this gear meshes with a bevel gear 111 secured on the hollow shaft 27, so that the solid material turrets 59 and 63 and the liquid material turrets 87 and 88 are geared together and operate one with the other. The hollow shaft 95 has the shaft 99 extending through the same, and its lower end extends down below the bottom of the hollow shaft and below the bevel gear 109, as shown in Figure 1.

15 The bottom of the shaft 68 fits within a socket 113 on the extension 114 of the regulating member 116. This regulating member is slidably mounted on a rod 117, and is operated by means of a screw 118 mounted on a bracket 119, which said bracket 20 is in turn mounted on the bearing bracket 121. The screw 118 has a bevel gear 122 which meshes with a bevel gear 123 on the end of a shaft 124 mounted in the upstanding bearing 126, and said shaft has a hand wheel 127 on its outer end, so that upon the turning of said hand wheel, the bevel gears 123 and 122 will be operated, which will turn the screw 118, and operate the member 116 to raise or lower the shaft 68, and thus either push the upper turret 63 upward to increase the 30 capacity of the telescopic measuring cups of the lower and upper turrets 59 and 63, or by drawing the shaft 68 downward permit the weight of the hopper and turrets 59 and 63 to lower the said shaft 68, and thereby decrease the capacity of the 35 said telescopic cups. The regulating member 116 has an overhanging arm 128 to which is attached a link 129. This rod has its upper end fixed to a toothed rack 131 which is slidably mounted at the rear of an indicating dial 132. This dial is 40 mounted on the partition or plate 54. This slide- 45 able mounting consists of a slot 133 in said rack, and pins or screws 134 passing through said disk and through said slot, so that the rack is freely movable upward and downward, when the over- 50 hanging arm 128 is moved by the regulation of the shaft 68. The toothed rack 131 meshes with a pinion 136 centrally mounted on said indicating disk by means of a pin having a shoulder 137 to which is secured a finger 138. The indicating disk 132 is provided with a circle of closely spaced holes 139, which said holes are utilized for receiving the spring button 141 shown in Figure 6A.

In the canning industry, different packers have different systems for grading peas, etc., and in the case of peas may have four or more grades, depending upon the size of pea. Of course, small peas will pack considerably more compact than large peas, and therefore in changing from one grade to another, it will be necessary to alter the capacity of the telescopic measuring cups for measuring the peas to be deposited into the can. When, for instance, the machine is being initially used, and the proper regulation for a Number 1 grade pea has been obtained with the telescopic cups, one of the spring buttons 141 can be slipped into the hole 139 indicated by the finger 138, and thereafter the machine need only be regulated until that finger points to the button in order that the operator will know that the telescopic cups are properly set for a Number 1 grade pea. In like manner, the Number 2, Number 3, and Number 4 grades may be set by the use of the buttons, after the telescopic cups are properly regulated for those grades.

75 In Figure 6 there has been shown a button

142 indicating where the finger 138 should point when the telescopic cups have been set for Number 2 grade. Figures 7 and 8 illustrate an indicating device for the telescopic cups which measure the liquid in the liquid tank 93. The end of 5 the shaft 99 rests within the socket 143 in the extension 144 of the regulating member 146. This regulating member is operated by the screw 147 and extends up through the table 28, and is provided at its upper end with a bevel gear 148, 10 which meshes with a bevel gear 149 on a shaft 151. This shaft and the screw 147 are both mounted in the bearing bracket 152, and the shaft 151 is provided at its outer end with a hand wheel 153, so that upon the turning of 15 the said hand wheel, the shaft 151 will rotate the bevel gear 149 which, in turn, will rotate the bevel gear 148, and the shaft 147, and thus tend to raise or lower the regulating member 146 which tends to raise or lower the shaft 99 20 in the hollow shaft 95, so that the plugs 97 are either raised or lowered in the cups 96, thus changing the capacity thereof.

Of course, the shafts 68 and 99 may be split at X and Z respectively (see Figure 11), so that 25 only the resulting short stub shafts at the top need be rotated, and when the machine is cleaned only the small stub shafts would be withdrawn from the hollow shafts. In such a case the lower part of the interior shafts may be fixed 30 in the sockets of the adjusting members, as shown at S. (See Fig. 5.)

The regulating member 146 has an overhanging arm 145 to which is pivotally mounted a link 145', while the upper end of said link is 35 pivotally mounted at 150 to a rack 131 identical with that shown in Figure 5. This rack operates a pinion 136 at the back of an indicating dial 155, which is identical in construction with the dial 132 shown in Figures 5 and 6, 40 and the pinion operates a finger 155a in exactly the same manner as that explained in connection with Figures 5 and 6. The dial 155 is provided with a series of small holes 155' into 45 which the spring buttons 141 are inserted when the proper regulation of brine is obtained for filling the cans, containing the several grades of peas, or other discrete solid matter. It can be readily understood that when small peas are inserted into the can, the percentage of voids 50 will be much less than when large peas are inserted. Consequently, the telescopic liquid cups in the liquid tank 93 would have their capacities decreased, when the smaller peas are being put into the cans. However, the buttons will be inserted at the points on the dial to correspond 55 with the buttons on the solid material dial 132, so that a Number 3 on each of the dials would indicate the regulation for the cups of the solid material on the dial 132, and the regulation for 60 the liquid material on the dial 155.

The supporting frame 53 is provided with a liquid pot 154 which has ears 156 fastened to said frame by bolts 157. This pot has a flat bottom 158 with an intake recess 159 and a discharge recess 161. The discharge recess has an opening 162 which communicates with a spout 163 which has a flange 164 bolted against the outside of the pot by means of the bolts 166. This spout has its open end 167 directly over 70 the line of travel of the cans A as they are fed to the star wheel 36. The side of the brine pot opposite to the spout 163 has a nipple 168 adapted to receive a pipe 169 which extends to and communicates with the brine tank 93, so that 75

the common level of liquid is maintained in said tank and pot. This pot has an upstanding bearing 171 while a rotary measuring device 172 has a central sleeve 173 which fits down over said sleeve and is provided with a pair of lugs 174 which strike against a pin 176 on the end of a shaft 177 which extends through the bearing 171. The rotary measuring device has the major part of its bearing surface 178 flat and contiguous with the bottom 188 of the pot, and is provided with a pair of pockets 179 and 181 for obtaining a measured quantity of liquid from the recess 180 and carrying it around to the opening 182 from which it passes out through the funnel 183 to the can A. This rotary measuring device 172 is operated by means of a gear 182 which meshes with an idler gear 183, which said idler gear meshes with a gear 184 on the can feeding shaft 186. The pockets 179 and 181 are each provided with a vent pipe 187 which has an overhanging lid 188, so that said pocket may readily fill and discharge, while the overhanging lids 188 will prevent any dirt or dust from entering the said vent pipes.

Figure 9 shows the piping arrangement of the can filling machine wherein the supply of liquid consisting of brine, sauce, or other material, is fed from the pipe 189 to a valve 191 and from that valve through the pipe 192 to a valve 193 located in the bottom of the liquid tank 93. This valve 193 is operated by the ball float 194. The ball float 194 is adapted to maintain a level of liquid indicated at 196. Between the valve 191 and pipe 192 is a union 197 which has a threaded nipple 198 from which a small pipe 199 leads and passes around, and is provided on its end with an elbow 201 having a nipple 202 which enters the tapered collar 203 of the cover plate 78 at a point directly below the hopper 17. This nipple communicates with small flaring holes 204, so that a small quantity of liquid is fed at the bottom of the hopper to provide lubrication to assist the discrete solid matter in dropping rapidly into the telescopic cups of the turrets 59 and 63 as said cups pass under said hopper. Mounted on the table 28 is a bracket 204 which has a collar 206 surrounding the pipe 192 for maintaining the same in place, while the bottom end of said bracket is provided with a ribbed extension 207 having a bearing 208 at its outer end, which said bearing houses a valve shaft 209, which operates the gate 211 in the valve 191. This shaft 209 has a grooved collar 212 with fingers 213 resting therein, while governing balls 214 are fixed to arms 216 depending from said fingers so that when the shaft 209 is at rest the weight of the said balls will push the collar 212, and consequently the shaft 209 upward and seat the gate 211 firmly over the port 217 in said valve. The bottom end of the shaft 209 is provided with a small bevel pinion 218 which meshes with a bevel gear 219 on a shaft 221, and the inner end of this shaft is also provided with a bevel pinion 222 which meshes with a bevel gear 223 on the can feed operating shaft 186.

It will thus be seen that when the machine commences to operate by throwing in the clutch through the operation of the shipper handle 23 that the can feeding mechanism will be operated, so that the shaft 186 will be rotated. This rotation is communicated to the shaft 221 through the bevel gears 223 and 222 while the bevel gears 219 and 218 impart rotary motion to the shaft 209, thus throwing the governor balls 214 outward,

which motion through the operation of the toggle arms 216 opens the gate 211 opening the port 217 of the valve 191.

When the machine ceases to operate, the governor balls 215 will assume the position shown in Figure 9 which will effectively close off the passage of liquid from the pipe 189 into the union 197 and pipe 192, so that no liquid will be fed through the pipe 189 into the bottom of the hopper through the small openings 204, and no liquid can seep in through the valve 193 to the liquid tank 93, and since the height of the liquid in the liquid tank 93 controls the height of the liquid in the pot 154, no additional liquid can be fed into such pot, and, therefore, there will be no danger of the 15 brine tank and pot 154 overflowing.

Of course, it will be understood that while the machine has been described in detail showing certain specific constructions of mechanism to perform certain definite objects, the inventions 20 themselves are of a broad nature, bringing into a high speed can filling machine, functions which are novel, and which have not heretofore been found in this art.

The pre-briner or liquid pot utilizes spare time 25 of the machine in the feeding of the can to position for receiving its preliminary supply of brine or liquid, and when the discrete solid material is deposited therein, the liquid will be displaced, and will assume a higher level, so that less time will be 30 required in the operation of the machine for depositing into the can the necessary amount of liquid or brine to completely cover the solid matter therein. Moreover, the several adjuncts herein described and consisting of the indicating 35 means coupled with regulating means will be found of great benefit to canners and packers who heretofore have been compelled to resort to the "cut and try" method for regulating the telescopic cups, and the liquid flow being positively 40 cut off by governing means operated by the operation of the machine will insure the complete cut-off when the machine is brought to rest.

Of course, the machine illustrated and described may be modified in many and various 45 ways without departing from the invention herein set forth and hereafter claimed.

The invention is hereby claimed as follows:

1. A can filling machine provided with means for feeding cans to mechanism which revolves 50 same about an axis, dispensing means arranged to deposit a measured quantity of liquid into each can during said feed, and separate means for thereafter measuring and depositing into each can quantities of discrete solid material and then liquid during said rotary movement, said dispensing means being operated by said solid material measuring means.

2. A can filling machine provided with means for feeding cans to mechanism which revolves 60 same about an axis, a pre-liquid dispensing device comprising a liquid supply pot having air vented closed pockets revolving therein for measuring quantities of liquid for deposit into the cans during their feed to said revolving mechanism, and means for thereafter depositing first solids then additional liquid to said cans while in said revolving mechanism.

3. A can filling machine provided with means for feeding cans to mechanism which revolves 70 same about an axis, a liquid pot having rotary dispensing means arranged to deposit a measured quantity of liquid into each can during said feed, and separate means for thereafter measuring and depositing into each can quantities of discrete 75

solid material and then liquid during said rotary movement, said dispensing means being operated by said solid material measuring means.

4. A can filling machine provided with means for feeding cans to mechanism which revolves same about an axis, a liquid pot having a rotary member with pockets concentrically arranged to deposit a measured quantity of liquid into each can during its feed to the revolving mechanism, and means for measuring and depositing into each can quantities of discrete solid material and then liquid during said rotary movement.

5. A can filling machine provided with means for feeding cans to mechanism which revolves same about an axis, rotary dispensing means arranged to deposit a measured quantity of liquid into each can during said feed, and separate means for measuring and depositing into each can quantities of discrete solid material and then liquid during said rotary movement, said dispensing means being operated by said solid material measuring means.

6. A can filling machine provided with means for feeding cans to mechanism which revolves same about an axis, a liquid pot having rotary dispensing means arranged to deposit a measured quantity of liquid into each can during said feed, and separate means for measuring and depositing into each can quantities of discrete solid material and then liquid during said rotary movement, said dispensing means being operated by said solid material measuring means.

7. A can filling machine provided with means for feeding cans to rotary mechanism, a liquid pot having rotary means arranged to deposit a measured quantity of liquid to each can during its movement to said rotary mechanism, a hopper for discrete solid material, turret means arranged to measure and deposit a predetermined quantity of material from said hopper into each can during its rotary movement, a liquid tank having means thereon for measuring and depositing an additional quantity of liquid to each can during its rotary movement whereby the solids in the cans are completely covered by liquid, said liquid pot rotary means being operated by said turret means.

8. A can filling machine provided with means for feeding cans to rotary mechanism, an open liquid pot having a rotary member with pockets arranged to deposit a measured quantity of liquid to each can during its movement to said rotary mechanism, a hopper for discrete solid material, turret means arranged to measure and deposit a predetermined quantity of material from said hopper into each can during its rotary movement, a liquid tank having means thereon for measuring and depositing an additional quantity of liquid to each can during its rotary movement whereby the solids in the cans are completely covered by liquid, said liquid pot rotary means being operated by said turret means.

9. A can filling machine provided with means for feeding cans to rotary mechanism, an open liquid pot arranged to deposit a measured quantity of liquid to each can during its movement to said rotary mechanism, a hopper for discrete solid material, adjustable turret means arranged to measure and deposit a predetermined quantity of material from said hopper into each can during its rotary movement, a liquid tank having adjustable means thereon for measuring and depositing an additional quantity of liquid to each can during its rotary movement whereby the solids in the cans are completely

covered by liquid, said liquid pot rotary means being operated by said turret means.

10. A can filling machine provided with means for feeding cans to rotary mechanism, an open liquid pot having a rotary member with pockets arranged to deposit a measured quantity of liquid to each can during its movement to said rotary mechanism, a hopper for discrete solid material, adjustable turret means arranged to measure and deposit a predetermined quantity of material from said hopper into each can during its rotary movement, said liquid pot rotary member being operated by said turret means, a liquid tank having adjustable means thereon for measuring and depositing an additional quantity of liquid to each can during its rotary movement whereby the solids in the cans are completely covered by liquid.

11. A can filling machine provided with means for feeding cans to rotary mechanism, an open liquid pot having rotary measuring pockets arranged to deposit a measured quantity of liquid to each can during its movement to said rotary mechanism, a hopper for discrete solid material, turret means arranged to measure and deposit a predetermined quantity of material from said hopper into each can during its rotary movement, said liquid pot rotary measuring pockets being operated by said turret means, a liquid tank having means thereon for measuring and depositing an additional quantity of liquid to each can during its rotary movement whereby the solids in the cans are completely covered by liquid, and means automatically adjustable through the adjustment of the capacity mechanisms to indicate the capacities of the solids and liquid from the tank deposited into each can.

12. A can filling machine provided with means for feeding cans to rotary mechanism, an open liquid pot having rotary measuring pockets arranged to deposit a measured quantity of liquid to each can during its movement to said rotary mechanism, a hopper for discrete solid material, adjustable turret means arranged to measure and deposit a predetermined quantity of material from said hopper into each can during its rotary movement, said liquid pot rotary measuring pockets being operated by said turret means, a liquid tank having adjustable means thereon for measuring and depositing an additional quantity of liquid to each can during its rotary movement whereby the solids in the cans are completely covered by liquid, and means automatically adjustable through the adjustment of the capacity mechanisms to indicate the capacities of the solids and liquid from the tank deposited into each can.

13. A can filling machine having means for feeding cans into position to be filled, means for depositing a limited and measured quantity of liquid to each can during such feeding, devices each comprising upper and lower turrets providing telescopic measuring cups, one device having means for supplying discrete solid material to its cups and the other having means for supplying liquid to its cups, separate means for adjusting the capacities of the cups of each device, and separate means each operated by one of the adjusting means of the devices for indicating the capacities of the cups of each device.

14. A can filling machine having a pair of measuring devices each comprising an upper and a lower turret providing telescopic measuring cups, one of said devices having means for supplying discrete solid material to its cups and the other having means for supplying liquid to its

- cups, means for supplying a measured quantity of liquid to each can before supplying solid material, means for progressively depositing the solid and then the liquid material from the cups, 5 means associated with each device for adjusting the relationship of said turrets to regulate the capacities of said cups, said adjustment being effected through means which permit the free removal of the upper turrets for cleansing the devices and their replacement without changing the adjustment of the measuring cups, and separate means each operated by one of the adjusting means of the devices for indicating the capacities of the cups of each device.
- 15 15. A can filling machine having a liquid pot for supplying a measured quantity of liquid to each can as same enters the machine, said machine having upper and lower rotary turrets providing telescopic measuring cups, a distributing member below said turrets and provided with directing funnels, a stationary plate between said turrets and distributing member having an opening for discharging material from said cups through said funnels into cans to be filled, a hollow shaft provided with drive means and having the lower turret and distributing member secured thereto, a stub shaft secured to the upper turret and extending into the hollow shaft, and a non-rotatable shaft in said hollow shaft abutting said stub shaft and provided with means for raising and lowering same whereby the relationship between the turrets is adjusted to alter the capacity of the cups.
- 30 16. A can filling machine having a liquid pot for supplying a measured quantity of liquid to each can as same enters the machine, said machine having upper and lower rotary turrets providing telescopic measuring cups, a distributing member below said turrets and provided with directing funnels, a stationary plate between said turrets and distributing member having an opening for discharging material from said cups through said funnels into cans to be filled, a hollow shaft provided with drive means and having the lower turret and distributing member secured thereto, a stub shaft secured to the upper turret and extending into the hollow shaft, a non-rotatable shaft in said hollow shaft abutting said stub shaft and provided with means for raising and lowering same whereby the relationship between the turrets is adjusted to alter the capacity of the cups, and means operated through the operation of said last-named means for indicating the cup capacity.
- 45 17. A can filling machine having a pair of measuring devices each comprising an upper and a lower turret providing telescopic measuring cups; one of said devices having means for supplying discrete solid material to its cups and the other having means for supplying liquid to its

18. A can filling machine having a pair of measuring devices each comprising an upper and a lower turret providing telescopic measuring cups, one of said devices having means for supplying discrete solid material to its cups and the other having means for supplying liquid to its cups, a distributing member having funnels each adapted to successively receive the contents of the solid material cup and liquid cup and to direct same into a can to be filled, hollow shafts for rotating each of said lower turrets, each upper turret having a solid shaft secured thereto and extending through its respective hollow shaft, said internal shafts each provided with means for raising and lowering same whereby the relationship between the turrets is adjusted to alter the capacities of the cups, and separate means each operated by one of said last-named means for indicating the cup capacity.
19. A can filling machine having means for feeding cans to be filled, a liquid pot having means arranged to deposit a measured quantity of liquid to each can during feeding, a hopper for discrete solid material, means arranged to deposit a predetermined quantity of material from said hopper into each can, a liquid tank, means for supplying liquid to said tank, means in said tank for measuring and for depositing an additional quantity of liquid to each can whereby the solids in the cans are completely covered by liquid, and means in the supply means of said tank for automatically shutting off said supply when the machine ceases to operate.
20. A can filling machine having means for feeding cans to be filled, a liquid pot having a rotary member with pockets arranged to deposit a measured quantity of liquid to each can during feeding, a hopper for discrete solid material, means arranged to deposit a predetermined quantity of material from said hopper into each can, a liquid tank, means for supplying liquid to said tank, means in said tank for measuring and for depositing an additional quantity of liquid to each can whereby the solids in the cans are completely covered by liquid, and means in the supply means of said tank for automatically shutting off said supply when the machine ceases to operate.
